UNITED STATES PATENT OFFICE

2,003,692

DENTAL APPLIANCE

James E. Meadows, San Francisco, Calif.

Application April 16, 1934, Serial No. 720,700

2 Claims. (Cl. 32—19)

This invention relates to a dental device employed for recording the bite of the teeth and gums of patients. This device is similar to the one shown in my United States Patent No. 1,518,868, dated June 25, 1929.

The object of my invention is to provide a more flexible device than heretofore employed whereby the proper "bite" of a patient's jaws may be recorded with absolute accuracy in a plastic substance, such as wax, which record is adapted to be transferred to the dental articulator.

In the drawing Fig. 1 is a side view of the device in a closed position.

Fig. 2 is a view similar to that of Fig. 1 with the arms of the device slightly opened.

Fig. 3 is a side view of the device with the arms open and angularly positioned relatively differently from the view of Fig. 2.

Fig. 4 is an enlarged view of the outer end of one of the arms of the device, showing the wax tray more in detail, and with a portion of the device in section.

Fig. 5 is a plan view of Fig. 4.

Heretofore considerable difficulty has been encountered in procuring a record of the correct normal "bite" of the patient's jaws. Some patients persist in abnormally protruding or withdrawing the lower jaw when biting into the plastic material for making the record that is used to fashion the dentures, and as a result the dentures made from such records are faulty and must be made over, sometimes many times, before the correct record is made.

I overcome this difficulty by use of an appliance that permits the patient to bite into the wax in the ordinary manner, but which also supports the record thus made against the gums of the patient when the jaws of the patient are widely opened without the record shifting relative to the gums or teeth, as the case may be.

Since the relative position of the upper and lower jaws of the patient, when the patient's mouth is widely opened, is correct, should there be an error in their relative position when the "bite" is made, it will be rectified by use of my device upon the movement of the jaws to the open position. The two impressions are locked relatively against movement radially of the axis extending through the jaw pivots when the jaws are in open position; hence, when the jaws are closed, the impressions or wax records may be sealed together and received from the patient's mouth, such record being absolutely correct.

In detail, my device comprises arms 1, 2, pivotally connected together at adjacent ends by a

pivot 3 to open and close compass-like. Extension arms 1', 2' are respectively connected at one of their ends to an end of arms 1, 2, by pivots 4, 5. Pivots 3, 4, and 5, are all arranged to permit the arms to move in the same plane.

From point 7 outwardly to their free ends the extension arms 1', 2', are cylindrical as at 8 and of reduced cross-sectional diameter for longitudinal sliding into a cylindrical recess extending longitudinally into elongated tray supporting members 9 which are of substantially the same outside cross-sectional shape as the arms 1', 2'. Members 9 are each longitudinally slotted along one side at 10 for passing a screw 11 transversely through the slot preventing parts 8 and 9 from turning relatively. Screw 11 is threaded into the cylindrical end 8 of the arms 1', 2', and at its outer end is provided with a head 12 for turning, the head being adapted to engage the side margin of the slot 10 when tightened for securing the member 9 against longitudinal movement relative to part 8. When loosened, however, the member 9 is free for sliding longitudinally of part 8 in both directions, except that its inward movement is limited by the shoulder formed at point 1.

The outer ends of members 9 are offset inwardly toward each other at 13, and each of said members terminates at its extreme outer end in a flattened tubular member 14 having an opening therethrough for receiving a flat extension 15 of a tray 16, which tray is shaped and adapted to support the impression wax on one of its sides for receiving the impression of the gums and teeth of a patient.

These trays 16 are flat and are adapted to come together on the sides opposite their wax supporting sides when the arms of the device are brought together.

Since there often is a variation in the pivotal points of the jaw of the patient, whereby the lower jaw will move laterally slightly at some point or other between the open and closed position upon opening the jaw, I secure the plate 15 in the flattened tubular member 14 by a screw 17 that threadedly extends through a boss 45 formed on a broad side of said flattened tubular member, and which screw is pointed at its end engaging the plate 15, thereby permitting each of the trays to pivot laterally around the pointed end of the screw. I do not desire to restrict myself to a pointed screw, but any pivotal connection that is adapted to release the plate 15 for withdrawal from the tubular member when desired is sufficient, although my showing is preferable since it is sim-

ple, effective, and permits a wide variety of adjustment of the pivotal point. It is, of course, obvious, as shown in the drawing, that the flattened opening in tubular member 14 is 5 sufficiently wide relative to the width of the plate 15 to permit the plate and consequently the tray, to be pivoted.

In some instances the articulator that mounts the trays is not adapted to take a very long 10 plate, such as 15, and in such case I provide the tray with an extension 20, slotted along one edge as at 21 in the plane of the tray, and which slot receives an edge of plate 15, being connected against withdrawal therefrom by a spring-urged 15 latch 22 on plate 15 adapted to engage on a catch 23 on extension 20.

Thus by releasing the engagement between the latch and catch, the tray may easily be separated from the plate.

20 In order to provide for arms 1, 2, 1', 2', opening and closing together and assuming corresponding angular positions relatively, I provide links 25, 26, of equal length pivotally connected at one of their ends respectively at 27, 28 to 25 arms 1, 2, at points equi-distant from pivot 3, and at their opposite ends, links 25, 26 are pivotally connected together at 29.

Arms 1', 2', are also provided respectively with links 30, 31 connected at one of their ends 30 to said links respectively at 32, 33, said pivots being equi-distant respectively from pivots 4, 5. Links 30, 31 are slightly longer than links 25, 26 and at their ends opposite pivots 32, 33 are pivoted together by pivot 34.

35 Pivots 3, 29, and 34 extend respectively transversely through straight slots 35, 36, 37, in a flat elongated guide bar 38, which slots are in longitudinal alignment along the bar 38. Said pivots are slideable longitudinally in the slots, 40 thus permitting greater flexibility than was possible in the device of my previous patent, and allowing the trays to assume correspondingly angular positions of any degree relatively and at any degree of separation of the trays 16 on 45 opposite sides of a medial line 40 extending longitudinally of bar 38.

In operation, the patient bites into the wax 11, indicated in dotted line in Fig. 1. One of screws 17 is loosened and the patient's jaws are 50 opened to their extreme open position, which might be as is indicated in Figs. 2 or 3, according to the patient. Any error in the bite is rectified by reason of the fact that the loosened tray is free to slide longitudinally of member 55 8. Also, by reason of the fact that all of pivots

3, 29, and 34, are free to slide in their respective slots, the wax impression will remain tightly against the gums of the patient in exactly the same relation as when the "bite" was recorded. When the jaws of the patient are 5 opened as widely as possible, the loosened screw is tightened, and the patient then closes his or her jaws. Since the arms 1', 2', must come together exactly as they were at the time of making the "bite", and since the correct "bite" was 10 registered when the jaws of the patient were opened, there can be no error in the position of the two impressions when the trays are again brought together. The wax impressions are 15 then sealed along adjacent edges and the impressions removed from the patient's mouth as a unit, which unit, with the trays, separated from the arms and the subsequent operations for making the denture are continued.

Having described my invention, I claim:

20 1. A dental appliance comprising a pair of arms pivotally connected at one end, each of said arms being provided with a pivotal joint at a point intermediate its ends the pivotal joints being equi-distant from the pivot connecting the ends of the arms whereby each of said arms comprises an inner section pivotally connected at an end to an end of the inner section of the opposite arm and an outer section pivotally connected to the free end of each inner section respectively, a pair of mouth trays on the free outer ends of the outer sections of the arms, means whereby the arms are controlled for simultaneous pivotal movement comprising a pair of links pivotally connected at 35 one end and each link pivotally connected at its opposite end to one of the outer sections of the arms respectively, and a member provided with elongated slots in longitudinal alignment, said slots arranged and adapted to slidably receive the pivot connecting the ends of the inner sections of the arms and also the pivot connecting the ends of the links for slideable movement of both pivots longitudinally of the slots.

2. In a device as defined in claim 1, a second 45 pair of links pivotally connected at one end and each of said second pair of links pivotally connected at its opposite end to one of the inner sections of the arms respectively, the pivot connecting the ends of said second pair of links 50 being disposed within one of the slots in said slotted member for slideable movement longitudinally of said slot.

JAMES E. MEADOWS.
